US0D1074347S

(12) **United States Design Patent** (10) **Patent No.:** **US D1,074,347 S**
(45) **Date of Patent:** **** May 13, 2025**

(54) **LAWN MOWER**

(71) Applicant: **Jiangyun Xu**, Hunan (CN)

(72) Inventor: **Jiangyun Xu**, Hunan (CN)

(**) Term: **15 Years**

(21) Appl. No.: **29/941,161**

(22) Filed: **May 8, 2024**

(51) **LOC (15) Cl.** **08-03**

(52) **U.S. Cl.**

USPC **D8/8**

(57) **CLAIM**

The ornamental design for a lawn mower, as shown and described.

DESCRIPTION

FIG. 1 is a first perspective view of a lawn mower showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1; and,

FIG. 9 is an environmental perspective view thereof.

The broken lines in the drawings depict portions of the lawn mower that form no part of the claimed design.

1 Claim, 9 Drawing Sheets
